GLASS BANDING MACHINE

John C. E. Schwab and Hobart M. Wheeler,
 Clarksburg, W. Va., assignors to Hazel-Atlas
 Glass Company, Wheeling, W. Va., a corpora-
 tion of West Virginia

Application October 2, 1933, Serial No. 691,838

7 Claims. (Cl. 91—12)

The invention relates to the decoration of tum-
 blers and other glass articles, and particularly to
 the painting of colored bands thereon.

Heretofore the general practice has been to
 5 apply by hand painted bands to tumblers and
 other glass articles. This hand practice is neces-
 sarily slow and expensive, and also irregularities
 naturally occur in the bands when thus applied.
 The object of the present invention is to provide
 10 a simple apparatus by which the bands will be
 automatically painted on the glass articles,
 whereby the operation will not only be performed
 quickly and inexpensively, but also the paint will
 be applied more regularly than has been possible
 15 with hand operations.

Various objects and advantages of the invention
 will be apparent to those skilled in the art
 from the following detailed description when
 taken in connection with the accompanying
 20 drawings, in which,

Figure 1 is a perspective view of the apparatus;
 25 certain parts being omitted for the sake of clear-
 ness; and,
 Figure 2 is a side elevational view of one of
 the units; parts being in section and parts being
 broken away to more clearly illustrate the con-
 struction.

Referring to the drawings in more detail, num-
 30 eral 1 indicates a frame which supports the
 various parts of the machine. In the specific
 form illustrated the apparatus is driven by a
 motor 2 carried by the frame. The motor shaft
 is coupled with a shaft 3 mounted in suitable
 35 bearings carried by the frame. This shaft car-
 ries a worm gear 4, which, through appropriate
 gearing, causes rotation of the chuck or vacuum
 cup 5 in the direction of the arrow. This cup
 or chuck 5 is in constant communication with
 40 any desired source of vacuum (not shown) by a
 pipe 6. The tumbler or other article to be dec-
 orated, indicated by numeral 7, is placed in the
 chuck by hand and is maintained there by the
 vacuum during the decorating operation.

Numeral 8 refers to a fixed shaft which is to
 45 the rear and above the article to be decorated.
 In the specific form illustrated this shaft is car-
 ried by a bracket 9. A number of arms 10 are
 pivotally mounted on the shaft 8. Three of these
 arms are shown in the drawings, but of course
 50 the number of arms will depend upon the num-
 ber of bands to be applied to the glass article.

As stated above the arms 10 are pivotally
 mounted on the shaft 8, so that they are free to
 be swung toward and from the article to be dec-
 orated, but it is also desirable to adjust these

arms along the shaft to properly position the
 bands on the article. Any desired means may
 be employed for this purpose, but in the pre-
 ferred form illustrated the arms are provided
 with forked upper ends 11 through which the 5
 shaft 8 passes, and between the prongs of each
 fork is a lug 12 which is adjustable along the
 shaft by means of a set screw 13.

Mounted on the lower end of each of the arms
 10 is an individual paint reservoir 14. The means 10
 for supplying paint to these reservoirs will be
 described hereinafter. A paint applying roller 15
 is also carried by each of these arms; the rollers
 being free to rotate through the paint in the
 reservoirs and to be brought into contact with 15
 the glass article when desired. The lower ends
 of the arms 10 are normally urged toward the
 glass article by springs 16; and it will be under-
 stood that as the arms are independent of each
 other, each roller 15 may move inwardly a dif- 24
 ferent distance, until each roller contacts with
 the tumbler or other article to be decorated, so
 that the rollers will contact with the article what-
 ever the contour of the article may be. 25

In the specific form illustrated the rollers con-
 tact with the article at the side thereof. In the
 event that a large number of bands are to be
 applied to the article, it is desirable to employ
 two sets of the paint-applying rollers to contact
 with the article at different points, and the rollers 30
 of the two sets being staggered. For this pur-
 pose a second fixed shaft is provided, as indi-
 cated by numeral 17, and the desired number of
 arms 18, similar to the hereinbefore described
 arms 10, are pivotally mounted on this shaft. 35
 These arms are individually adjustable longitudi-
 nally of the shaft by the same means as de-
 scribed in connection with the arms 10, and the
 lower ends of the arms are normally urged to-
 ward the glass article to be decorated by means 40
 of springs 19. It will be noted however that the
 arms 18 instead of being substantially straight
 like the arms 10 are somewhat L-shaped, so that
 the rollers 15 of the arms 18 contact with the
 underside of the glass article. It will be under- 45
 stood that either or both sets of arms 10 and 18
 are employed, depending upon the number of
 bands to be applied to the article.

Numeral 20 refers to a frame which is pivotally
 mounted on the bracket 9. This frame includes 50
 two rods 21 and 22; the rod 21 being in front of
 the arms 10, and the rod 22 being in the rear
 of lugs 23 which project upwardly from the arms
 18. The frame is provided with an operating
 lever 24, and it will be noted that when this lever 55

- is moved downwardly the rods 21 and 22 will cause both sets of arms to be moved away from the article, for the purpose of removing the paint-applying rollers from contact with the article. When the operator releases the lever 24 the spring 25 will swing the frame back to the position shown in Figure 1, thereby permitting the springs 16 and 19 to move the arms forwardly to bring the rollers into contact with the article.
- 10 At times it is desirable to keep the arms and rollers in their inoperative or withdrawn position without the necessity of the operator holding the lever 24 down. For this purpose a lug 26 is slidably mounted on the shafts 8 and 17.
- 15 The lever 24 having been lowered, the lug 26 is moved to the left (Fig. 1) until it comes under the frame 20. The lever may now be released and the lug 26 will hold the frame 20 carrying the rods 21 and 22 in such position that the arms 10 and 18 will be maintained in their withdrawn positions.

The paint-applying apparatus carried by the arms 10 and 18 will now be described; it being understood that this apparatus is identical on all the arms, except that the thickness of the rollers may vary according to the widths of the various bands to be applied, and the angular position of the rollers may also vary. A description of one of the units will be sufficient, and in connection with this description reference is to be had particularly to Figure 2. In the specific form shown a short pipe section 27 is adjustably clamped to each arm. Attached to the lower end of the pipe section is the individual reservoir 14, and attached to the upper end of the pipe section is a flexible hose for supplying paint to the reservoir. In the bottom of the reservoir there is an outlet passage 28 through which unused paint is exhausted and flows back to the original source of paint, as will be described hereinafter. The rollers 15 are mounted for free rotation on the lower ends of the arms. The rollers are rotated through contact with the article being decorated, and as they rotate they travel through the paint in the individual reservoirs and apply the paint to the article. A wiper finger 29 is preferably provided to remove excess paint from the rollers. The depth of the rollers in the reservoirs can be adjusted by adjusting up or down the pipe sections 27 which carry the reservoirs.

The means for supplying the paint to the individual reservoirs will now be described, reference being had to Figs. 1 and 2. Numeral 30 refers to the paint pots, of which in this particular machine there are three. These pots are charged with paint from time to time through the filling nozzles 31, which are threaded in elbows 32 formed in the plate 33. The paint flows through these elbows into the top of the paint pots. Of course the paint in these pots may be of the same or of different colors or shades. The pots are preferably removably attached to the underside of the plate 33. The specific attaching means shown consists of lugs 34 which are slidably mounted on pins 35 fixed to the plate 33; the lugs being forced upwardly by springs 36. The top of each pot is provided with a flange 37 which is interrupted at points to permit the passage of the lugs 34. To remove a pot it is only necessary to rotate it until the cut-out portions of the flange align with the lugs 34. When the pot is returned to its position the springs 36 will hold it up tight against the underside of the plate 33.

75 Numeral 38 refers to bevel gears keyed to the

shaft 3. These bevel gears mesh with bevel gears 39 fixed to shafts 40 which project downwardly into the paint pots 30. Pinned or otherwise secured to the lower end of each of the shafts 40 is a disc 41 from which a number of fingers 42 project downwardly. Through the mechanism described the motor 2 which rotates the article to be decorated also rotates the discs 41 and the fingers 42 carried thereby. The rotation of the discs and fingers causes a continuous stirring of the paint, keeping it properly mixed and of a uniform character throughout.

The fingers 42 have another function in addition to stirring the paint, in that they act as a coupling or clutch for driving the pumps which force the paint through the system. In the bottom of each of the paint pots is an ordinary rotating eccentric pump 43. The upwardly extending shaft of the pump is referred to by numeral 44, and the upper end of the shaft carries 20 a disc 45. This disc is provided with any suitable openings, such as indicated by numeral 46, for receiving the fingers 42. Thus when the paint pots are mounted in position the pumps are coupled with the shafts 40 which are continuously 25 rotated by the motor 2; and this coupling also permits the paint pots to be quickly removed.

From the foregoing description it will be noted that in this specific mechanism the motor 2 rotates the article to be decorated, and also operates 30 the stirring devices and the pumps, but it will be understood of course that any desired means may be employed for operating these several parts.

The pump 43 forces the paint through a pipe 47 up to a header 48 which is mounted upon the 35 upper end of a pipe 49. Within the header is a valve seat 50 with which the valve head 51 cooperates; the valve head being preferably provided with a number of apertures 52. A number of pipes 53 lead from each of the headers to 40 various individual reservoirs 14, each of such pipes being provided with a valve 54. In Figure 2 only one of these pipes is shown, but several are shown in Figure 1, and it will be understood that as many of the pipes as desired may be employed; 45 and which ones of them are to be connected up with the individual reservoirs will depend upon the number of bands to be applied, how many of the bands will be of the same color, etc. When the valve head 51 is lifted, as shown in Figure 2, 50 and the valves 54 are open, the paint will flow through the pipes 53 to the individual reservoirs, and from the reservoir through pipes 55 back to the pump. Thus a continuous flow of paint through the reservoir is maintained. The volume 55 of paint flowing into the pipes 53 may be regulated to some extent by the adjustment of the valve head 51, and the volume flowing through each of the pipes 53 to the reservoirs may be regulated by the valves 54, and the volume flowing 60 back to the pump through the pipes 55 may be regulated by the valves 56. In the specific form illustrated the pipes 55 lead to a manifold 57 and from the manifold a pipe 58 leads back to the pump, though of course each of the several pipes 65 55 could lead back directly to the pump if preferred.

If more paint is pumped to the headers 48 than is delivered from the headers to the individual reservoirs, the surplus will flow through 70 the apertures 52 into the pipe 49 and thence back to the paint pot. It is sometimes desirable, as when getting ready to put the machine into operation, to feed the paint through the system without delivering it to the individual reservoirs. 75

For this purpose a by-pass pipe 59 is provided. It leads directly from the header to the manifold and thence back to the pump; the by-pass pipes being preferably provided with valves 60.

5 In the foregoing description of the system through which the paint flows from the pump to the header and thence to the individual reservoir and then back to the pump, only one of the systems has been described, but there may be 10 any desired number of the systems, three of them being shown in the particular apparatus illustrated. The description of one of the systems or units is sufficient as they are all identical in construction.

15 The functions of the various parts have been described in connection with the description of the apparatus, and therefore a very brief description of the operation will suffice. The motor, or other driving means, rotates the chuck, and 20 when the tumbler or other article to be decorated is placed by hand in the chuck it is held there by vacuum. The motor also drives the stirrers 42 and the pumps 43 in the paint pots 30. When 25 the apparatus is in operation the valve heads 51 are open and the pumps force the paint from the pots to the headers 48, from which the paint flows to the desired individual reservoirs 14 and thence back to the pumps as described hereinbefore; valves being provided to regulate the 30 flow to and from the individual reservoirs. The paint being in proper condition, and the flow having been properly regulated, and the reservoirs having been adjusted to bring the rollers 15 to the desired depth in the reservoirs, the device 35 is ready for decorating the articles. Having placed an article in the chuck 5, the operator moves the lug 26 to the right (Fig. 1) thereby permitting the springs to move the arms toward the article, bringing the rollers into contact 40 therewith. The rollers come into contact with the article whatever its contour may be, for each arm is movable independently, and hence each arm will move inwardly under the pressure of its spring until its roller contacts with the article 45 to be decorated.

The article is rotating when the paint-applying rollers contact with it, and this causes the rotation of the rollers. The rollers gather paint as they turn through the body of paint in the 50 individual reservoirs and apply this paint to the article in the form of bands. Only a very few turns of the article are necessary to complete the decoration, and the operator now depresses the lever 24 to move the rollers away from the article, removes the article from the chuck, replaces it with another article, and then lifts the lever 24 or permits the spring 25 to lift it to again bring the rollers into operation, thus starting another cycle. The number of arms employed 55 will depend upon the number of bands to be applied to the article; and of course the arrangement of the bands may be varied at will to produce any desired effect.

60 While we have described in detail the preferred construction, it will be understood that various changes and modifications may be made without departing from the spirit of the invention, and all such changes and modifications are intended to be included within the scope of the appended 65 claims.

What we claim is:

1. An apparatus for painting bands on tapered glass articles, including a plurality of pivotally mounted arms, a roller and an individual reservoir carried by each arm, means for continuously supplying paint to the individual reservoirs, means individual to each arm for independently moving the arms different distances toward the tapered glass article, and means common to all the arms for moving the arms away from the article. 5

2. An apparatus for painting bands on glass articles, including a plurality of pivotally mounted arms, a roller and an individual reservoir carried by each arm, means for continuously supplying paint to the individual reservoirs, means individual to each arm for moving the arms toward the article, means common to all the arms for moving the arms to inoperative position, and means for locking the arms in inoperative position. 15

3. An apparatus for painting bands on articles, including a series of arms, a roller and an individual reservoir carried by each arm, a second series of arms, a roller and an individual reservoir carried by each of the arms of the second series, and the arms of the two series being arranged in staggered relation. 25

4. An apparatus for painting bands on glass articles, including a series of arms, a roller and an individual reservoir carried by each arm, a second series of arms, a roller and an individual reservoir carried by each of the arms of the second series, the arms of the two series being arranged in staggered relation, means individual to the arms of both series for moving the arms independently toward the article and means common to the arms of both series for moving them to inoperative position. 30

5. An apparatus for painting bands on glass articles, including a plurality of rollers and reservoirs individual to each roller, resilient means for bodily moving each roller and reservoir toward the article, means for continuously supplying paint to the individual reservoirs, means for continuously returning paint from the reservoirs to the source of paint, and valves for regulating the volume of paint flowing through each individual reservoir. 45

6. An apparatus for painting bands on glass articles, including a plurality of rollers and reservoirs individual to each roller, resilient means for bodily moving each roller and reservoir toward the article, a paint pot, a header, a pump continuously supplying paint from the pot to the header, delivery lines leading from the header to a plurality of the individual reservoirs, and the valves for regulating the volume of paint flowing through each individual reservoir. 55

7. An apparatus for painting bands on glass articles, including a reservoir and a roller, means for moving the reservoir and roller toward the article, a paint pot, a header, a pump continuously supplying paint from the pot to the header, a delivery line leading from the header to the reservoir, a return line leading from the reservoir to the paint pot, and an overflow line leading from the header back to the paint pot. 60
